APPARATUS FOR RECEIVING DELIVERED
COMMODITIES AND PREVENTING THEFT
THEREOF

Arthur Sutcliffe, London, England

Application October 28, 1937, Serial No. 171,586
In Great Britain September 25, 1936

4 Claims. (Cl. 232—42)

This invention relates to an apparatus to be installed on the joint of a doorway or other structure in the proximity of a door, and which is intended to receive delivered commodities and prevent theft thereof. The apparatus is so constructed that after the receiving element thereof has been set to receiving position and the goods inserted, it can be turned to a position in which access to its contents is obstructed by the door, 5 means being provided for preventing said receiver being returned to the aforesaid receiving position so that the contents are inaccessible except by opening the door. The invention is applicable to street and apartment doorways and also to doors 10 of lift cages in cases where goods are inserted into one side of said cage and removed from the other side.

According to the invention there is provided an apparatus comprising, in combination, a receiver rotatably mounted in a carrier, an opening 20 in said receiver by way of which goods can be inserted into it, a base member adapted to be fixedly mounted on a door frame and constructed so that the receiver-carrier slides vertically down 25 said base member to engage it, a catch device on the base member, engaged by the door when closed for locking the receiver-carrier in the engaged position, and means to prevent the turning of the receiver from its non-accessible position 30 whilst the door remains closed.

The locking of the receiver in the carrier when it has been turned to non-accessible position may be effected by providing means for ensuring unidirectional movement of the receiver in the carrier, the receiver being formed of non-circular shape or otherwise constructed to present a projection adapted to contact with the door when the receiver is turned to non-accessible position. Further turning to reset to receiving position can- 35 not be carried out until the door has been opened and no longer obstructs the movement of the receiver. Opening of the door also permits access being had to the interior of the receiver, and also releases the locking catch aforesaid to permit bodily removal of the receiver should this be desired.

A preferred form of apparatus in accordance with the invention will now be described and is shown in the accompanying drawing, wherein:—

50 Figure 1 is a part sectional elevation of the apparatus,

Figure 2 is a vertical section on line II—II in Figure 1, showing the base member and the portion of the receiver-carrier which is engaged 55 therewith, and

Figure 3 is a cross-section on line III—III in Figure 1.

Referring to the drawing, there is provided a base member for attachment to the jamb of a door, said base member comprising an elongated plate 4 having its longitudinal side portions 5 turned over forwardly to form channels which terminate short of the bottom of said plate. On the remaining lower portions 6 of the plate is mounted on a centrally disposed pivot 7 a catch member 8 having one limb projecting to form a thumb piece 9. Another limb thereof upstands and forms a detent 10. The catch is adapted to swing out to an extent determined by shoulder 11, which is adapted to contact with a centrally positioned stop 12 on the plate, while the thumb piece serves as a counterweight automatically to normally turn the detent 10 into the channel. A cover plate 13 is provided to fit over the lower part of said catch and said cover plate 20 may carry the pivot stud 7 for said catch.

The receiver comprises a container 14 which is somewhat pear-shaped in cross-section, i. e. part-circular formation having tangential portions meeting to form a projecting corner 15, one 25 of said tangential portions being constituted by a door 16, having the hinge at the corner 15. This container is pivotally mounted between upper and lower horizontal arms 17 extending from a straight bar constituting the carrier, the 30 edges of the bar being adapted to enter the channels of the base member. Near to one end said bar 18 is formed with a notch 19 in one side edge, and a similar notch 19 is formed in the same edge near the opposite end. 35

When said bar 18 is slid into proper engagement with the base member one of the notches 19 is positioned to receive the detent 10 of the catch.

The carrier incorporates a ratchet and pawl 40 device comprising a ratchet wheel 20 attached to the pivot stud 28 of an arm 17 of the carrier bar 18, a disc 21 attached to the receiver 14, pawls 22 mounted on diametrically opposite pivots 23 on said disc 21, and pawl-actuating springs 45 24 fitted on diametrically-opposite pins 25 set at 90 degrees to the pawl pivots 23, the pawls engaging the ratchet wheel 20. This arrangement permits of the ratchet wheel 20 and pawls and spring being reversed if desired when changing the device from a left-hand opening door to a right-hand opening door.

The device is mounted in close relation to a door 25 so that the catch 8 is prevented from 55

turning by the final closing movement of the door, thus locking the receiver carrier in place.

To convert from left-hand operation to right-hand operation it is only necessary to reverse the catch 8 from one side to the other. The container is now inserted in inverted relation to its previous disposition to ensure that its door 16 faces the street or like door 25. This inversion also reverses the ratchet-controlled direction of turning although if preferred the ratchet itself may be changed for reverse operation as hereinbefore explained.

With the device constructed in the manner above set forth there is the remote risk of the receiver becoming jammed if its door 16 should have been left open instead of having been closed when turning said receiver beyond the position in which its access opening faces the street or like door, that is to say the door 16 may be caught 20 and obstructed by the carrier bar 18. Since the pawl and ratchet devices prevent reverse turning of the receiver necessary to free the door in these circumstances, there is provided a trigger 26 pivotally movable about an extension 27 of the receiver-carrying pivot stud 28, said trigger, when manipulated being adapted to raise the pawls from the ratchet wheel 20, and permit reverse turning of the receiver. As the trigger is accessible only from the interior of the receiver it 30 cannot be tampered with in attempted theft.

I claim:—

1. An apparatus adapted to be supported on a door jamb adjacent a hinged door for receiving delivered commodities and preventing theft thereof, said apparatus, comprising, in combination, a receiver having an opening by way of which goods can be inserted into it, a carrier having a vertical portion provided with a notch in one edge and formed at its ends with laterally offset arms, means for rotatably mounting said receiver between said arms, a base member adapted to be attached to the door jamb and comprising a strip having channel edges for slidably receiving the vertical portion of said carrier, a catch device 45 mounted on the base member and having a part adapted to project therefrom for contact with the door, a detent on said catch device for engagement with said notch in the carrier, and means to prevent the turning of the receiver from a non-accessible position while the door remains closed.
2. An apparatus adapted to be supported on a door jamb adjacent a hinged door for receiving delivered commodities and preventing theft thereof, said apparatus comprising, in combination, a receiver having an opening by way of which goods can be inserted into it, a carrier for said receiver adapted to be reversed end for end for right and left hand use, said carrier including a vertical portion provided in one edge thereof 60 with upper and lower notches and also having

laterally off-set arms, means for rotatably mounting said receiver between said arms, a base member adapted to be mounted on the door jambs and comprising a strip having channel edges for slidably receiving the vertical portion of said carrier, a catch device reversibly mounted on the base member for right or left hand use and having a part adapted to project therefrom for contact with the door, a detent on said catch device for engagement with one of said notches in the carrier, and means to prevent the turning of the receiver from a non-accessible position while the door remains closed. 5

3. An apparatus adapted to be supported on a door jamb adjacent a hinged door for receiving delivered commodities and preventing theft thereof, said apparatus comprising, in combination, a receiver having an opening by way of which goods can be inserted into it, a carrier for said receiver adapted to be reversed end for end for right and left hand use, said carrier including a vertical portion provided in one edge thereof with upper and lower notches and also having laterally off-set arms, means for rotatably mounting said receiver between said arms, a base member adapted to be mounted on the door jamb and comprising a strip having channel edges for slidably receiving the vertical portion of said carrier, a catch device reversibly mounted on the base member for right or left hand use and having a part adapted to project therefrom for contact with the door, a detent on said catch device for engagement with one of said notches in the carrier, and means to prevent the turning of the receiver from a non-accessible position while the door remains closed, said means comprising a pawl and ratchet for insuring unidirectional turning of the receiver, and pawl lifting means accessible only from the interior of the receiver. 30 25

4. An apparatus adapted to be supported on a door jamb adjacent a hinged door for receiving delivered commodities and preventing theft thereof, said apparatus comprising, in combination, a support adapted to be secured to the door jamb, a casing mounted for partial rotation in said support, said casing including a body having end walls and a side wall including circular and tangential wall portions, and a cover also formed with substantially circular and tangential wall portions, said tangential wall portions of the body and cover being hinged together, said hinged portions of the body and cover, when located near the support on the door jamb permitting the cover to be opened, and when moved toward the door being obstructed by the door; and pawl and ratchet means at one of the end walls of the body for compelling manual movement of the hinged portion of the body of the casing and cover toward the door. 40 45 50 55
